US00D853986S

(12) **United States Design Patent** (10) **Patent No.:** **US D853,986 S**
(45) **Date of Patent:** **** Jul. 16, 2019**

(54) **HEADPHONES**

(71) Applicant: **Apple Inc.**, Cupertino, CA (US)

(72) Inventors: **Eric Treski**, Manhattan Beach, CA (US); **Christina J. Smiechowski**, Hollywood, CA (US); **Robert D. Brunner**, San Francisco, CA (US); **Christopher Kuh**, San Francisco, CA (US); **Achille Biteur**, San Francisco, CA (US)

(73) Assignee: **Apple Inc.**, Cupertino, CA (US)

(**) Term: **15 Years**

(21) Appl. No.: **29/615,486**

(22) Filed: **Aug. 29, 2017**

Related U.S. Application Data

(63) Continuation of application No. 29/557,250, filed on Mar. 7, 2016, now Pat. No. Des. 796,474.

(51) **LOC (11) Cl.** **14-01**

(52) **U.S. Cl.**

USPC **D14/205**

(58) **Field of Classification Search**

USPC D14/205, 223; D29/112; 2/209, 175.4, 2/195.4; 181/129, 130, 135; 379/430, 379/431; 381/380, 381, 374; 455/90.3, 455/575.1, 569.1

CPC H04R 1/1066; H04R 1/1016; H04R 5/033; H04R 5/0335; A42B 1/06

(57) **CLAIM**

The ornamental design for headphones, as shown and described.

DESCRIPTION

FIG. 1 is a top front perspective view of headphones showing the claimed design;

FIG. 2 is a bottom front perspective view of thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The broken lines in the figures show portions of the headphones that form no part of the claimed design.

1 Claim, 7 Drawing Sheets
